[57] CLAIM

The ornamental design for a mounting bracket for a
handgun or similar article, as shown and described.

DESCRIPTION

FIGS. 1 and 2 are respectively front and rear perspective
views of a mounting bracket for a handgun or similar
article showing my new design;

FIG. 3 is a side elevational view thereof, the side oppo-
site being a mirror image; and,

FIGS. 4 and 5 are respectively front and rear eleva-
tional views thereof.

FIG. 1

FIG. 2

FIG. 3

FIG. 4

FIG. 5
